POLE GAINING MACHINE

Gilbert Vivian Cook, Denver, Colo.

Application November 28, 1947, Serial No. 788,362

2 Claims. (Cl. 144—133)

1

This invention relates to a pole gaining machine, that is, to a device for notching telephone, telegraph, and electric pole line poles for the reception of the wire-carrying cross arms. Such poles are provided with one or more horizontally extending notches or gains of a width to snugly receive a cross arm. The cross arm is secured in the gain by means of a single cross arm bolt extending through the pole. The gains are usually formed by hand. The hand operation is a slow, tedious one, and unless done by experts, results in gains of varying widths and varying inclines.

The principal object of this invention is to provide an economical and highly efficient motor-driven machine which will rapidly and accurately form the gains in the poles at the desired points so as to eliminate hand labor and obtain accurate gains.

Another object of the invention is to so construct the device that it will automatically adjust itself to accurately form gains in poles of various sizes and various tapers.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side elevation of the improved pole gaining machine, as it would appear in use;

Fig. 2 is a plan view thereof;

Fig. 3 is a front view; and

Fig. 4 is a detail section, taken on the line 4—4, Fig. 2.

In the drawing, a conventional pole is indicated at 10. The pole is carried on a dolly 11 provided with track wheels 12 running upon suitable track rails 13. The pole is supported on the dolly upon rollers 14, which allow it to be rotated to place any selected side of the pole upwardly. The improved pole gaining machine is also mounted on track rails 15 extending at right angles to the rails 13.

The machine comprises a carriage 16 supported from the rails 15 upon track wheels 17. The carriage is provided with transversally aligned bearings 18. A tubular boom 19 is supported by the carriage. The boom 19 is provided intermediate its extremities with two sidewardly ex-

tending stub shafts 20 which are welded or otherwise permanently secured to the boom 19 and project from opposite sides thereof. The stub shafts 20 are journaled in the bearings 18 so that the boom is free to tilt upwardly and downwardly.

A motor platform 21 is carried on the rearward extremity of the boom 19 to support a drive motor 22 and a cutting head is supported by the forward extremity of the boom 19. The cutting head is supported from a rotatable sleeve 23 which is slipped over the forward extremity of the boom 19 and positioned between two set collars 24. A U-shaped yoke plate 25 is welded or otherwise secured to the sleeve 23 with its furcations extending forwardly therefrom.

The furcations of the yoke 23 each carries a shaft bearing 26, through which a rotatable shaft 27 extends carrying a plurality of dado blades 28 intermediate the bearings 26. The shaft 27 is rotated through the medium of a driven pulley 29, from which an endless belt 30 extends to a drive pulley 31 mounted on the shaft of the motor 22.

A side plate 32 extends upwardly from each side of the yoke plate 25 to support a cross hinge member 33. A connecting rod 34 extends from the cross hinge member 33 to a second cross hinge member 35, which is supported from the carriage 16 upon bracket arms 36. The cross members 33 and 35 are positioned directly above the shafts 27 and 20, respectively, the distance between the shafts and the cross members being uniform. With this arrangement a parallelogram is formed which maintains the side plates 32 vertical at all angular positions of the boom 19.

The lower edges of the side plates 32 are turned outwardly to form flanges 37, from each of which a horizontal runner 38 is suspended upon adjustable suspension bolts 39. Handle brackets 40 extend forwardly from the flanges 37 to support a handle bar 41.

In operation, the pole is moved along the rails 13 to the proper position for a cross arm gain. The pole is rotated on the rollers 14 to place the selected side upward. The operator then pulls downwardly on the handle bar 41, to bring the rotating dado blades against the pole. The handle 41 is then moved forwardly and backwardly, the runners 38 sliding upon the pole, and the carriage 16 moving on the rails 15, to quickly cut a gain across the top side of the pole.

It is desired to call attention to the fact that

the entire working head may rotate upon the boom 19 to accommodate any taper in the pole. The depth desired for the gain is pre-set by regulating the suspension bolts 39, to set the runner at any desired spacing above the lower edges of the dado blades 28. The stub shafts 20 are so positioned relative to the extremities of the boom 19 so that the weight of the motor 22 will slightly over balance the weight of the working head so that when the handle bar is released the dado blades will rise from the pole and so that very little effort will be required to bring the blades to the work.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A machine for forming cross arm receiving gains in poles comprising a carriage, bearings carried by said carriage, a boom extending longitudinally of said carriage and projecting from the front and rear ends thereof, stub shafts projecting from opposite sides of said boom and rotatably received in said bearings to pivotally mount the boom for vertical tilting movement, a motor at the rear end of the boom, a sleeve loosely mounted about the forward portion of said boom, a yoke carried by the sleeve and having legs projecting forwardly from the front end of the boom, a saw shaft rotatably mounted across the front ends of the legs of said yoke, blades carried by the shaft between the legs of the yoke and spaced from each other longitudinally of the shaft, means for transmitting rotary motion from the motor to the saw shaft, side plates loose about said saw shaft and projecting upwardly at opposite sides of said yoke, a front cross bar extending between the upper ends of said plates and rotatably supported thereby, brackets rising from said carriage with their upper ends disposed over said bearings, a rear cross bar rotatably supported over the stub shafts by said brackets, a rod connecting the cross bars and being spaced upwardly from said boom, outstanding side flanges along

5 the lower edges of said plates, screws passing vertically through said flanges and carrying runners at their lower ends and projecting downwardly therefrom, arms projecting forwardly from said flanges, and a handle bar extending between the front ends of said arms.

2. A machine for forming cross arm receiving gains in poles comprising a carriage, a boom extending longitudinally of said carriage and projecting forwardly and rearwardly therefrom and being pivotally mounted for vertical tilting movement about a horizontal axis over the carriage, a yoke mounted for tilting movement about the front end portion of the boom circumferentially thereof and having legs projecting forwardly from the boom at opposite sides thereof, a saw shaft rotatably mounted across the legs and extending therebetween, blades carried by the saw shaft and disposed between the legs of the yoke in spaced relation to each other longitudinally of the shaft, plates at opposite sides of the yoke tiltably mounted about the saw shaft and projecting upwardly from the yoke, brackets rising from said carriage with their upper ends disposed over the horizontal axis of the boom, a rod extending longitudinally of the boom in upwardly spaced parallel relation thereto and having cross bars at its front and rear ends rotatably engaged with the upper ends of the plates and the brackets, flanges along the lower edges of the plates, arms projecting forwardly from said flanges, a handle bar carried by the front ends of said arms, and runners supported under said flanges and adjustable vertically.

35 GILBERT VIVIAN COOK.
